UNITED STATES PATENT OFFICE.

WALSEY A. FREDERICK, OF MOUNTAIN LAKES, NEW JERSEY, ASSIGNOR TO WESTERN ELECTRIC COMPANY, INCORPORATED, OF NEW YORK, N. Y., A CORPORATION OF NEW YORK.

ACOUSTIC DEVICE.

Application filed May 19, 1924. Serial No. 714,477.

This invention relates to acoustic devices and particularly to telephone receivers.

An object of the invention is to provide an efficient and economical earphone which 5 may be comfortably retained in the ear of the user without the aid of external support.

The invention is adapted for use as an auricular telephone for the aid of the hard of hearing, and may also be used to advantage 10 as a telephone operator's receiver, as well as for many other purposes.

According to a feature of the invention, a miniature telephone receiver and an earpiece or mounting member are assembled in 15 a compact, unitary structure, the mounting member being molded to conform to the contour of the meatus of the individual user.

This construction requires no headband or other external support and hence renders the 20 receiver very inconspicuous. This construction, furthermore, affords an efficient acoustic coupling and, because of its light weight and the absence of undue pressure upon the ear, adds materially to the comfort 25 of the user. By molding the mounting member to fit the ear of the individual user the earphone is firmly held in place and affords substantially the same efficient coupling in different individuals.

Because of the close fit between the mounting member and the ear of the user, this earphone reduces to a minimum the sound which escapes around the mounting member, a factor which is of considerable importance 30 in situations where sound given off by the receiver might prove a source of considerable annoyance to other persons in the vicinity.

The various features and advantages of 40 the invention will appear from the following description taken in connection with the accompanying drawing, in which,

Fig. 1 is a view partially in section illustrating the invention.

Fig. 2 is a perspective view thereof; and

Fig. 3 is a perspective view illustrating the manner in which the device is applied to the ear.

As shown in Fig. 1, the compact earphone 50 comprises a mounting member or earpiece 5 and a miniature telephone receiver which may be of any suitable construction.

The receiver may, for example, be of the electromagnet type disclosed in the patent 55 application of Warren C. Jones, Serial No.

714,476, filed May 19, 1924. This receiver comprises a cylindrical case 6 having a central pole piece 7, carrying an electromagnet coil 8, and a diaphragm 9 which is clamped to the case 6 by means of a threaded cap 10. 60 The usual sound passage 11 is provided in the face of the cap 10, adjacent the diaphragm 9. The receiver cords 12 extend through the hole 13 in the case 6, or may be brought out in any other convenient manner. 65 A plurality of flanges or ridges 14 may be formed in the periphery of the receiver cap 10 for a purpose hereinafter to be described.

The mounting member 5 is formed of 70 gutta-percha, rubber compound or any other suitable plastic material, and is preferably colored to resemble the flesh of the user. The mounting member 5 is molded to conform to the contour of the meatus or 75 conspicuous outer chamber of the ear of the individual user. A sound canal 15 is formed to extend through the mounting member, terminating at one end in the extension or protuberance 16 which is adapted to register 80 with and if desired to extend into the auditory duct of the ear.

The receiver cap 10 is assembled in the mounting member 5 in any suitable manner. The cap may be affixed to the mounting 85 member adhesively or by means of supporting pins or may be embedded therein during the molding process. In the construction shown in the drawing the receiver cap is embedded in the mounting member during 90 the molding process, the molding material being pressed firmly over the flanges 14 in order to insure a firm bond between the mounting member and receiver cap. In molding, the cap 10 is so positioned in the 95 mounting member 5 that the sound passage 11 registers with the canal 15 in order to insure the free transmission of sound vibrations from the diaphragm 9 to the auditory duct of the ear. The molding material completely covers the receiver cap 10 and conceals it from view, leaving only the small cylindrical case 6 exposed.

The compact earphone described above may be readily adjusted in the meatus of 105 the ear to present a neat and pleasing appearance, as shown in Fig. 3. The exposed portion of the mounting member 5 is suitably rounded off to conform to the outer ridges of the ear. By molding the earpiece 110

5 to fit the ear of the individual user, the device may be snugly and firmly adjusted in place, thus assuring an efficient acoustic coupling and at the same time effectively securing the device against accidental displacement. The light weight of this earphone and the absence of any undue pressure on the ear add materially to the comfort of the user. Due to the fact that the 10 mounting is molded to fit the individual ear, the weight is well distributed over the surface of contact so that there are no points of excessive pressure on any portions of the ear.

15 The invention set forth herein is, of course, susceptible of various modifications and adaptations, and accordingly the invention is not to be considered as limited except as defined by the scope of the appended 20 claims.

What is claimed is:

- 25 1. In an earphone, a mounting member conforming substantially to the meatus of the ear, and a telephone receiver embedded in said mounting member.
2. In an earphone, a mounting member

molded to conform to the meatus of the ear, a sound canal extending through said mounting member and terminating at one end in an extension adapted to be inserted in the 30 auditory duct of the ear, and a telephone receiver molded in said mounting member adjacent the other end of said canal.

3. In combination, a small, light weight telephone receiver, and a mounting member 35 therefor molded to the ear of the individual user to fill a substantial part of the outer ear and to distribute the weight substantially uniformly over the major portion of the surface of contact with the ear.

4. A telephone receiver and a mounting member forming the sole support for said receiver 40 said mounting being molded to fit the interior of the outer ear of the individual user and being of such dimensions that when in place in the ear, it is contained entirely within the outermost limits of the auditory 45 passage into the ear.

In witness whereof, I hereunto subscribe my name this 19th day of May, A. D., 1924.

HALSEY A. FREDERICK.
